The ornamental design for a pan, as shown and described.

DESCRIPTION

FIG. 1 is a perspective view of a pan of the present invention, showing our new design;

FIG. 2 is a top view thereof;

FIG. 3 is a bottom view thereof;

FIG. 4 is a front view thereof;

FIG. 5 is a rear view thereof;

FIG. 6 is a right side view thereof; and,

FIG. 7 is a left side view thereof.

Broken lines are used to illustrate features of the pan that form no part of the claimed design.
